UNITED STATES PATENT OFFICE.

WILBUR I. ARMSTRONG, OF BELVIDERE, ILLINOIS, ASSIGNOR TO HIMSELF
AND ALFRED THOMAS ARMSTRONG, OF SAME PLACE.

PAINT-DISTRIBUTER.

SPECIFICATION forming part of Letters Patent No. 311,631, dated February 3, 1885.

Application filed July 7, 1883. (Model.)

To all whom it may concern:

Be it known that I, WILBUR I. ARMSTRONG, of Belvidere, Boone county, Illinois, have invented a new and Improved Paint-Distributer, 5 of which the following is a full, clear, and exact description.

The object of my invention is to provide a new and improved device for distributing pigments and other liquids.

10 The invention consists in a distributor provided with a spoon-shaped receptacle for receiving the liquid to be distributed, into which receptacle a feeder projects which is formed of two spring-strips, between which the liquid 15 is drawn by capillary attraction, and is then distributed by a current of air.

The invention also consists in an air-receiver through which the compressed air passes before reaching the distributor, and whereby the 20 air will be moistened, and thus keep the parts of the distributor clean.

Reference is to be had to the accompanying drawings, forming part of this specification, in which similar letters of reference indicate 25 corresponding parts in all the figures.

Figure 1 is a plan view of my improved distributor. Fig. 2 is an end view of the same, partly in section, and Fig. 3 is a side view of the air-receiver, parts being broken out and 30 parts shown in section.

A spoon-shaped receptacle, A, is fastened to the bottom of a block of wood, B, at one end of the same, so that the said receptacle projects beyond the end of the piece of wood. 35 The said receptacle is provided with a transverse groove, C, terminating in a point or lip, C'. A feeding device, D, consists of a metal strip bent to form two spring-shanks united at the base ends by a cross-piece, and the 40 opposite pointed ends being held in contact with each other, in the same manner that the points of an ordinary drawing-pen are held in contact, or nearly so. The feeder D is attached at its base end to a spring, E, fastened to the 45 end of the block B, and provided with a screw, F, for adjusting the tension of the spring. The feeder is inclined downward from the spring E, the point of the feeder projecting slightly beyond the lip C'. The shank of the 50 feeder adjoining the end of the block is connected by a wire, G, with an arm, H, on the

lower end of a shaft, H', journaled vertically on the end of the block or piece of wood, and provided at its upper end with a handle, J. The air-conducting tube K is provided at its 55 end with a vertical nozzle, L, the point of which is directly above the point of the feeder D. The air-tube is provided with a cock, M, fastened to a sleeve, N, on which a spring, O, acts, which keeps the cock closed. The tube K 60 is connected by a flexible tube, P, with an air-receiver, Q, into which the compressed air is conducted by a tube, R. The air-receiver is adapted to contain water for moistening the compressed air, which water can be heated by 65 means of a lamp, S, &c.

The operation is as follows: The liquid to be distributed is poured in small quantities on the receptacle A, or is fed on the same in some suitable manner. By capillary attraction the 70 liquid is drawn into the slot in the feeder, and passes down the same to the point of the feeder, and is blown to atoms by the compressed air issuing from the lower end of the nozzle L. If the liquid is to pass to the point of the feeder 75 more rapidly, the points of the prongs must be drawn apart, which is accomplished by turning the handle J of the shaft in such a manner that the shank of the feeder toward the end of the block B is drawn from the other 80 shank of the feeder. The compressed air absorbs moisture while passing through the receiver Q, and this moisture causes the pigment to flow more freely and keeps the several parts of the atomizer clean. 85

Having thus described my invention, I claim as new and desire to secure by Letters Patent—

1. In a paint-distributer, the combination, with a paint-receptacle, of a forked feeder extending over the edge of the paint-receptacle, 90 and an air-nozzle held directly above the point of the feeder, substantially as herein shown and described.

2. In a paint-distributer, the combination, with a spoon-shaped paint-receptacle, of an 95 inclined feeder provided with spring-shanks, and an air-nozzle held directly above the ends of the spring-shanks of the feeder, substantially as herein shown and described.

3. In a paint-distributer, the combination, 100 with a paint-receptacle, of a feeder having spring-shanks, a nozzle held directly above the

ends of the said spring-shanks, and a spring for separating the points of the shanks, substantially as herein shown and described.

4. In a paint-distributer, the combination, with the block B, the receptacle A, and the nozzle L, of the forked feeder D, the spring E, secured to the feeder and block, and the adjusting-screw F, substantially as herein shown and described.

10 5. In a paint-distributer, the combination, with the block B, the receptacle A, and the nozzle L, of the feeder D, having spring-shanks, the shaft H', provided with the arm H and the handle J, and the wire G, connected to

the said arm and to one of the shanks of the 15 feeder, substantially as herein shown and described.

6. In a paint-distributer, the combination, with the receptacle A and the forked feeder D, of the tube K, provided with the nozzle L 20 and cock M, the pivoted lever N, and the spring O, substantially as herein shown and described.

WILBUR I. ARMSTRONG.
